UNITED STATES PATENT OFFICE.

CURRAN C. WEEKS, OF CHICAGO, ILLINOIS, ASSIGNOR OF ONE-HALF TO
NELLIE B. LATIMER, OF SAME PLACE.

BELT.

SPECIFICATION forming part of Letters Patent No. 628,901, dated July 11, 1899.

Application filed May 1, 1899. Serial No. 715,131. (No model.)

To all whom it may concern:

Be it known that I, CURRAN C. WEEKS, a citizen of the United States of America, residing at Chicago, in the county of Cook and State 5 of Illinois, have invented certain new and useful Improvements in Belts, of which the following is a specification.

My invention relates to certain improvements in belts, designed to provide means for 10 so attaching said belts to the waistband of a skirt or other article of wearing-apparel that the one may be supported by the other and the two kept in the proper relative positions.

To such end the invention consists in certain 15 novel characteristics possessed by the preferred construction herein described, said characteristics being pointed out in the appended claims.

In the drawings, Figure 1 is a view of the 20 belt, showing the same in position upon a skirt and the rear portion of the belt cut away to reveal certain fastening devices upon the skirt-band. Fig. 2 is a perspective from the front of the belt alone, and Fig. 3 is a 25 longitudinal transverse section of the belt extended in a straight line.

In the drawings the belt is lettered A, and the waistband B. A flap C is secured at its 30 upper edge along the inside of the belt and has fastened on it a series of studs D, adapted to enter and be held by a series of spring-sockets E, secured to the waistband.

In attaching the belt to the waistband the flap is turned downward, the studs upon it

forced into the sockets, and the belt then 35 turned down over the flap, concealing it from view and distributing the pull of the skirt along a considerable portion of the belt.

The construction herein described can be varied from greatly without departing from 40 the principle of the invention, and I therefore do not limit myself to the exact details of the same.

I claim as new and desire to secure by Letters Patent—

1. The combination with a belt and waistband, of a flap, C, secured along its upper edge to the inside of said belt and capable of being swung away from said belt on the line of union therewith, a series of fasteners upon 50 said flap and a series of coacting fasteners upon the waistband adapted to engage therewith; substantially as described.

2. The combination with a comparatively rigid belt, of a flexible flap secured along its upper edge to the inside of said belt, a series 55 of spring-studs secured upon said flap and a series of coacting spring-sockets adapted to be secured to the waistband of a skirt and to engage said studs; substantially as described. 60

In witness whereof I have hereunto set my hand at Chicago, in the county of Cook and State of Illinois, this 27th day of April, A. D. 1899.

CURRAN C. WEEKS.
